WILLIAM C. SCHEU, OF UPLAND, CALIFORNIA, ASSIGNOR TO SCHEU PRODUCTS COMPANY, LTD., OF UPLAND, CALIFORNIA, A CORPORATION OF CALIFORNIA

LIGHTING TORCH FOR ORCHARD HEATERS AND THE LIKE

Application filed November 13, 1929. Serial No. 406,875.

This invention relates to a lighting torch for use in igniting the fuel in orchard heaters and the like, such lighting torch comprising in general a container for igniting fluid, an outlet pipe or spout on said container for delivery of a portion of such lighting fluid therefrom, a suitable wick adjacent to the outlet of said spout whereby a flame maintained on said wick serves to ignite the igniting fluid as it is delivered from said spout and whereby also the repeated delivery of igniting fluid through said spout serves to maintain the wick saturated with such fluid and support the igniting flame, and means for adjustably supporting the wick in position.

The principal object of this invention is to provide a lighting device of this type having improved means for supporting the wick within the spout with a portion of said wick projecting from the end of the spout, and particularly, a simple form of means whereby the wick may be adjusted into or out of the spout so as to cause the wick to project beyond the spout to any desired extent.

The lighting torch of my invention comprises essentially an igniting fluid container provided with an elongated tubular spout, a body of wicking material extending within said spout, a coil of wire or similar material wrapped around said wicking material and having open spaces between the adjacent turns thereof and means on said spout projecting inwardly and engaging between the turns of said coil of wire whereby rotation of said wire coil operates through engagement thereof with said inwardly projecting means to move the coil inwardly or outwardly in the spout in screw fashion and hence also move the wicking material inwardly or outwardly. The supporting coil for the wick fits somewhat loosely within the spout so as to permit flow of igniting fluid between the turns of the coil and the walls of the spout, and the outer end of said spout is preferably also provided with a suitable outwardly flared lip for promoting smooth outflow of the igniting fluid in a suitable sized stream therefrom.

The accompanying drawings illustrate an embodiment of my invention and referring thereto:

Fig. 1 is a side elevation of a lighting torch and a wick supporting means according to my invention. 55

Fig. 2 is a longitudinal section of the upper portion of the spout and wick shown in position for pouring igniting fluid therefrom. 60

Fig. 3 is a section on line 3—3 in Fig. 2. The lighting torch comprises a suitably shaped receptacle or container 1 for igniting fluid, which is shown in the present instance as a cylindrical container having a rounded top 2 and provided with a handle 3. Secured centrally of said top and extending upwardly therefrom is a tubular spout 4 provided at or adjacent its outer end with an inward projection 5 at one side which may be formed by simply bending this side of the spout inwardly at this position, and also provided at its upper end, and at the side opposite said inward projection, with an outwardly flared portion 6 providing a lip for promoting smooth flow of fluid therefrom. 75

Extending within the spout 4 is an elongated wick 7 consisting of a body of asbestos or other suitable wicking material, said wick extending into the spout to any desired distance, for example to the position indicated at 7a and projecting beyond the end of the spout to any desired distance, for example as indicated at 7b. An open coil of wire 8 having spaces 9 between the successive turns thereof is wrapped fairly closely around the wick 7 so as to support said wick and cause the wick to move with said coil; said coil may extend throughout the entire length of the wick or throughout any desired portion thereof. While said coil fits somewhat loosely within the spout 4 so as to permit outward flow of igniting fluid it nevertheless is of sufficient diameter to cause the inward projection 5 to positively engage between the successive turns thereof when said coil is inserted in the spout so that inward or outward movement of said coil may be effected by turning the same in one di- 85 90 95 99

rection or the other. The pitch of said coil is relatively small so as to tend to hold the coil in any longitudinal position of adjustment in the spout.

5 In operating the above described lighting torch, a suitable supply of igniting fluid such as gasoline is placed in the container 1, for example by removing the spout from the top of the container and pouring such 10 fluid in through this opening and then replacing the spout, or through any other suitable filling opening. By tipping the container sufficiently a portion of this fluid may be caused to enter the spout and saturate 15 the wick 7, and the projecting portion 7b of said wick may then be ignited in any suitable manner. By turning the coil 8 in one direction or the other said coil and wick may be screwed inwardly or outwardly so 20 as to properly adjust the length of the projecting portion of the wick and give an igniting flame of the desired size.

The torch is then ready for use in igniting other bodies of fuel, for example for igniting a number of orchard heaters or the like. For this purpose, the igniting opening of the orchard heater or other apparatus is opened and the lighting torch is tipped so as to deliver a small amount of igniting 25 fluid through the spout 4 and lip 6 into suitable position for ignition of the fuel within said apparatus, for example upon the surface of the body of fuel therein. In passing from the lip 6, the igniting fluid 30 is ignited by the flame on the projecting portion of the wick, and the burning fluid therefore serves to ignite the fuel in the orchard heater or other apparatus. Furthermore a portion of the fluid passing through 35 the spout serves to continually saturate the wick and support the flame at the outer end thereof.

I claim:

40 1. A lighting torch for orchard heaters and the like comprising a container for igniting fluid provided with a tubular spout, a wick extending within said spout and projecting through the outer end thereof, said wick fitting loosely within said spout so as 45 to permit free passage of igniting fluid through said spout and around said wick upon tipping of said torch, and means supporting said wick within said spout and adapted to effect adjustment thereof longitudinally of the spout.

45 2. A lighting torch for orchard heaters and the like comprising a container for igniting fluid provided with a tubular spout, a wick extending within said spout, a supporting coil wrapped around said wick and also extending within said spout, and means on said spout and projecting inwardly and engaging between the turns of said coil so 50 as to permit screw adjustment of said coil

inwardly and outwardly with respect to the spout.

3. A lighting torch as set forth in claim 2, the outer end of said spout being also provided at the side opposite said inwardly projecting means with an outwardly flared lip for promoting proper delivery of fluid therefrom. 70

4. In a lighting torch, a tubular spout, a wick extending within said spout, a wire 75 coil extending around said wick and supporting the same and fitting loosely within said spout, and means projecting inwardly from one side of said spout adjacent the outer end thereof and engaging between the turns 80 of said coil.

In testimony whereof I have hereunto subscribed my name this 4th day of November 1929.
